[57] CLAIM

The ornamental design for an elbow pad, as shown.

DESCRIPTION

FIG. 1 is a top, front and right side perspective view of an elbow pad showing my new design;
FIG. 2 is a front perspective view thereof;
FIG. 3 is a rear perspective view thereof;
FIG. 4 is a left side perspective view thereof;
FIG. 5 is a right side perspective view thereof;
FIG. 6 is a bottom perspective view thereof; and,
FIG. 7 is a top perspective view thereof.
The broken lines in all views represent conventional stitching.
